FLOAT FOR SKIN-DIVERS

Donald R. Dotson, Costa Mesa, Calif.

Application December 27, 1954, Serial No. 33,688

Term of patent 14 years

(Cl. D71—1)

FIG. 1.

FIG. 2.

FIG. 3.

Figure 1 is a front elevational view of a float for skin-divers, showing my new design;

Figure 2 is a top plan view; and

Figure 3 is a side view.

I claim:

The ornamental design for a float for skin-divers, substantially as shown.
